UNITED STATES PATENT OFFICE.

ADELBERT D. EVANS, OF AURORA, ILLINOIS.

INK-WELL ATTACHMENT.

1,134,829.

Patented Apr. 6, 1915.

Application filed November 29, 1913. Serial No. 803,750.

To all whom it may concern:

Be it known that I, ADELBERT D. EVANS, a citizen of the United States, residing at Aurora, in the county of Kane and State of Illinois, have invented new and useful Improvements in Ink-Well Attachments, of which the following is a specification.

This invention relates to ink well attachments; and it has for its primary object the provision of means for preventing the pen from being inserted beyond a predetermined position in the ink.

Another object of the invention is the provision of a device of this character which will automatically accommodate itself to the level of the liquid in which it is mounted and one which will include a shutter or cut-off actuated under the direct engagement therewith of the pen.

With these and other objects in view, the invention consists of certain novel features of construction, combination and arrangement of parts, as will be hereinafter described and claimed.

In the accompanying drawings: Figure 1 is a vertical section through an ink well, showing the application of the attachment thereto; Fig. 2 is a similar view, showing the shutter actuated under the action of the pen so as to prevent the latter from being inserted beyond a prescribed or predetermined depth in the ink; Fig. 3 is a horizontal section on the line 3—3 of Fig. 1; and Fig. 4 is a perspective view of the sliding cutoff.

The device comprises a tube 1 split vertically or folded or rolled so that its vertical edges are spaced to permit of the formation therebetween of an intervening continuous vertical guide slot 2 and adjacent thereto the tube has one of its walls formed with a vertical series of ratchet teeth 3. The upper end of the tube is fitted on the reduced end 4 of a hollow sleeve 5, the latter having its bore widened into internally flared upper walls 6 to facilitate the guiding of the pen into the tube. The sleeve is adapted to be secured in an opening 7 in the top 8 of an ink well, such as the one shown herein at 9. However, I wish it to be understood that the form of well or container is not essential to an operation of the device to permit the pen to be furnished or supplied with a desired quantity or predetermined supply of ink.

The tube 1 is embraced by companion sections 10 of a vertically movable collar, and as shown the terminals 11 of the collar sections are secured in a float 12, the latter being preferably formed of cork and in addition to its being secured to the terminals 11 as described the collar sections 10 are provided with bendable portions 13, which are bent over the adjacent sides of the cork so as to hold the latter securely in applied position. The opposite terminals 14 of the collar sections are connected together by a rivet 15 which forms a pivot for a vertically tilting shutter or valve 16, whose shank or extension 17 is fitted between the portions 14. One of the collar sections is provided with a bracket 18, which is connected to an extension 19 of the valve or shutter 16 by a spring 20, and under the office of the latter, the valve is normally held across the tube, as will be understood.

The shank of the valve is adapted to extend through and to travel in the vertical slot 2. The said shank of the shutter or valve is provided with an attaching portion 21, which is secured to a float 22. The said shank of the valve or shutter is provided integrally with the extensions 19 with a stop tooth 23 and under the action of the spring 20, said tooth is normally held out of engagement with the adjacent ratchet teeth of the tube.

From this construction, it is obviously understood that the floats 12 and 22 of the vertically movable and tilting shutter constantly seek the level of the fluid contained in the well and that when the pen is inserted in the tube and the pressure thereof brought to bear against the shutter, the valve 16 of the latter will open only to such degree or position as may be necessary to furnish the pen with the proper amount of ink. When the valve or shutter is tilted by bringing the weight of the pen to bear thereagainst the tooth 23 will coact with an adjacent tooth on the tube 1 and, as a consequence thereof the tilting action of the valve will be limited.

From the foregoing description, taken in connection with the accompanying drawings, the construction and operation of the invention will be readily understood without requiring a more extended explanation.

Various changes in the form, proportion and the minor details of construction may be

resorted to without departing from the principle or sacrificing any of the advantages of this invention as claimed.

I claim:—

- 5 1. An ink well provided with a tube, a float, a valve supported by the float and mounted for tilting movement, and means for limiting the tilting movement of the valve therein.
- 10 2. An ink well provided with a tube, a float associated with the tube and movable thereon respectively on the rise and fall of liquid within the well, a valve mounted for tilting movements upon the float and disposed within the tube, means on the valve, and means on the tube, the latter coating with the first means to limit the tilting movement of the valve.
- 15 3. An ink well provided with a tube, a float associated with the tube and movable thereon respectively on the rise and fall of

liquid within the well, a valve mounted for tilting movements upon the float and disposed within the tube, means on the valve, means on the tube, the latter coating with 25 the first means to limit the tilting movement of the valve, and means for holding the co-acting first and second means normally inactive relatively.

4. An ink well provided with a tube, a 30 float movably supported upon the tube, a valve carried by the float and means to prevent the lowering of the float on the application of pressure of the pen against the valve and to also permit the valve to be tilted to a 35 predetermined position.

In testimony whereof I affix my signature in presence of two witnesses.

ADELBERT D. EVANS.
